UNITED STATES PATENT OFFICE.

MATTHIAS MILLER. KANDLE, OF SPRINGFIELD, MASSACHUSETTS, ASSIGNEE TO
KANDLE-BORN COMPANY, OF SPRINGFIELD, MASSACHUSETTS, A CORPORATION
OF MASSACHUSETTS.

PRINTING-PRESSES.

1,093,190.

Specification of Letters Patent. Patented Apr. 14, 1914.

Application filed July 5, 1913. Serial No. 777,528.

To all whom it may concern:

Be it known that I, MATTHIAS M. KANDLE, a citizen of the United States, residing at Springfield, in the county of Hampden and 5 State of Massachusetts, have invented certain new and useful Improvements in Printing-Presses, of which the following is a specification.

This invention relates to improvements in 10 printing machines, and the principal object of the invention is to provide means to accurately position a sheet of paper prior to its being fed into the press and prior to the printing operation. 15 The invention is particularly useful in accurately positioning a sheet of paper for multi-color printing in which it is necessary that the various colors are accurately applied to the picture being printed, as, for 20 example, pictures of flowers, birds, or animals.

A further object of my invention is to provide means to reject the sheet before it enters the press if it is inaccurately positioned; that is to say, the sheet will be thrown out before the printing operation occurs, thereby preventing the sheet being wasted.

A further object of the invention is to 30 provide means to automatically prevent the type-form from coming into contact with the impression cylinder.

Further objects and the nature of the invention will be fully described in the specification and will be particularly pointed out in the claims, reference being had to the drawings forming a part of the specification.

Referring to the drawings,—Figure 1 is 40 a side-elevational view of the invention showing the usual press feedboard and impression cylinder; the attachments applied thereto comprising, in general, the trip mechanism, the sheet-rejecting mechanism, 45 and the devices to operate and support the contact devices which serve to position the sheet prior to the printing operation; Fig. 2 is a plan view of the attachment showing the electrical contact devices for positioning the sheet, the bar on which these devices are mounted, the circuits connected to the contact devices, and the driving mechanism for the sheet-rejecting devices; Fig. 3 is a

5 detail sectional view of one of the electrical contact devices; Fig. 4 is a diagrammatical view of the electrical circuits, which includes the timing contact devices against which the edges of the sheet engage; Fig. 5 is a side elevational view of the mechanism for operating the contact-carrying carriage, the reset mechanism for the trip, the main gear on which the various cam-devices are placed. Fig. 6 is a sectional view on the line 6—6 of Fig. 5 passing through the axis of the main gear-wheel 55 66 and showing the interior construction and arrangement of the latch, the reset devices therefor, and the main gear-wheel which carries the cam-devices; Fig. 7 is a detail view on the sectional line 7—7 of Fig. 5, 70 showing the electro-mechanical latch for retaining and releasing the supporting means for the sheet contact devices, and a portion of the reset device therefor; Fig. 8 is a sectional view on the line 8—8 of Fig. 9, showing the reset devices; Fig. 9 is an edge elevational view of Fig. 5, looking from the left, showing the main gear-wheel which carries the various cams and the driving means therefor, also the timing contacts; 75 Fig. 10 is a detail view showing the grooved face of the main gear with the crank-rod for locking the trip-rod, also a portion of the electro-mechanical latch and the means for locking the same; Fig. 11 is an edge 80 elevational view of Fig. 10, looking from the left, showing the position of the parts relative to the main gear-wheel which operates and controls the reset mechanism; also the trip mechanism for the press impression cylinder; and Figs. 12 and 13 are views showing the independent adjustment of the sheet-ejector wheels with relation to the feed-board.

Referring to the drawings in detail,—10 85 designates the feed-board of the press on which the sheets to be printed are placed.

11 represents a portion of a press impression-cylinder which is mounted in the uprights 12 of the main frame by means of the 130 shaft 12' to which the main drive-gear 12² is secured.

Extending across the machine from one upright to the other is a rod 13 which is rotatably mounted in the uprights. Pivotally 135 attached to this rod are arms 14 that have

adjustably secured thereto at their ends the brackets 15. Rotatably mounted in one of the brackets 15 is a friction roller 16 which is normally out of contact with the impression-cylinder 11 but is designed to engage the cylinder when a sheet of paper is inaccurately placed or fed to the machine and is to be ejected, as will be fully described. The roller 16, when operated, drives a sprocket-wheel 17 over which passes a chain 18 to a second sprocket-wheel 19 that is secured to a stub-shaft 20 which is mounted for rotation in the bracket 15. Secured to the shaft 20 is a gear 22 which meshes with the gear 23 on the shaft 24 that carries the rubber-faced sheet-ejecting wheels 25. These wheels, by reason of the connection just described, will rotate in a direction opposite to the direction of rotation of the press impression-cylinder 11, as will be clear from the use of the gears 22 and 23,—the direction of rotation of the impression-cylinder being indicated by the arrow 26, and the direction of rotation of the sheet-ejector wheels being indicated by the arrows 27.

It was stated above that the wheel 16 is normally out of engagement with the impression-cylinder 11, and it should be stated that the ejector wheels 25 are also normally out of contact with the press feedboard 10, as shown in Fig. 1 by the space 28. The structure which sustains the roller 16 and the rollers 25 in an inoperative position, is the lift-rod 29 that is attached at its lower end to a cam-operated lever 30 that is pivotally secured to a casing or bracket-member 31 which is secured to one of the uprights 12 by means of the foot-piece 32. The upper end of the lift-rod 29 is provided with an angular-shaped arm 33, the upper surface of which engages a bent arm 34 (see Fig. 2) that is attached to an elbow-shaped member which is secured to the rod 35; the arms of the elbow-shaped member are indicated at 36 and 37. The arm 36 is pivotally connected to a link 38 which, in turn, is pivotally connected to a slidable rod 39 at the point 40. The rod 39 moves in a bracket 41 that is part of the bracket 15 and engages the feed-board to elevate the ejector wheels 25 out of contact with the sheet of paper when the same is accurately positioned. The arm 37 engages a set-screw 42 by means of which the pressure of the roller 16 on the impression-cylinder 11 may be varied to cause it to rotate. The sheet-ejector wheels 25 are independently adjusted by means of the mechanism shown in Figs. 12 and 13, in which shaft 24 that carries the wheels 25 is mounted for adjustment on the bracket 15 by means of the set-screw 25' that passes through the slot 25² in the plate 25³. This plate turns on pivots about the shaft 20, and by means of the set-screw 25' the pressure of the sheet-ejector

wheels 25 may be varied on the feed-board 10.

Clamped, by means of the screws 43, in the upper portions of the arms 15 is a spacing-tube 44 and located within this tube is the rod 35 to which the bent arm 34 is secured, as shown in Figs. 1 and 2.

In the normal operation of the machine, the frame brackets 15 which turn on the rod 13 at 13', are raised and lowered by means of the cam-operated lever 30 which is attached to the lift-rod 29 at 46 and is pivoted to the casing 31 at 47. The cam-operated lever 30 is formed with a shoulder 48 that engages the slidable stop 49 on the downward movement of the rod 29. When the shoulder 48 engages the stop 49, which is normally projected into the path of this shoulder, as shown in Fig. 7, the downward movement of the sheet-ejecting wheels 25 and the roller 16 is prevented. Should this slidable stop 49, however, when a sheet is inaccurately placed, be withdrawn, as will be explained, the wheels 16 and 25 will be operated from the press cylinder 11 and the sheet ejected or prevented from entering the press. The cam-lever 30 is operated by means of a roller 50 which engages the cam 51 that is secured to the shaft 52. As the roller 50 leaves the concentric surface 53, as shown in Fig. 5, the shoulder 48 engages the stop 49. If the stop 49 is retracted by means of the compression spring 54 when released by the electro-magnets 55, should a sheet be inaccurately placed on the feed-board, leaving any one of the sheet-engaging contacts 100 closed, permitting the electro-magnet 55 to operate, the lift-rod passes by the stop 49 and the sheet-ejecting wheels 25 are operated as described. When the roller 50 reengages the concentric surface 53, the lift-rod is 105 pushed upward and the arms 14 elevated as described to permit the placing of a sheet on the feed-board 10 beneath the sheet-ejecting wheels 25 and against the press-guides.

Coming now to the description of the mechanism by means of which the rod 49 is released and then reset in the position shown in Fig. 6 and the means by which the same is retracted when a sheet is inaccurately fed and the sheet-ejecting mechanism operated.

56 designates a main gear or operating member which is driven from the pinion 57 which, in turn, is driven from the gear 58 that is operated by the gear 12², motive power being transmitted thereto by any suitable means. The gear 58 is mounted for adjustment in the arms 59 which are pivotally supported on the main shaft 52. One of the arms is provided with an adjusting device 125 indicated at 60 which is merely a slot and screw construction.

The gear 56 is formed with a groove 61.

and in this groove is secured a curved-shaped cam 62 and a second cam 63 of less length than the cam 62 but terminating in the same plane as the cam 62, as indicated at 64 (see Fig. 10). The thickness of the cam 63 is greater than the cam 62. The purpose of the cams 62 and 63 is to set the electro-mechanical latch in locking position, which consists of an electro-magnet 55 having the latch 65 which normally retains the stop 49 projected as shown in Fig. 7. This latch is provided with a roller 66 which is normally retained elevated by a suitable spring (not shown). The latch, however, is of common construction.

Referring to Fig. 10, 67 designates a bearing in which is mounted a rod 68. Attached to one end of this rod is a crank-arm 69 or finger which lies back of the lever 70 (see Figs. 8 and 10). The other end of the rod 68 is connected by means of a pin-and-slot connection 71 and 72 with a member 73 which is formed with an arm 74 and a roller 75 pivoted thereon, as shown in these figures. The rod 68 has a bearing in the wall of the casing at 76. Also attached to the rod 68 is an arm 77 which has a slot-and-pin connection 78 with the transversely-located stop 49 whereby this stop may be moved to extend the same, as shown in Fig. 7. It will be seen that the rod 68 and arms 69 and 77 may be rocked when the roller 75 engages the cams 62 and 63 in the groove 61 when the wheel 56 is rotated in the direction of the arrow shown at 79. The spring 80 permits the wheel 75 to yield and move toward the center of the wheel 56 as the wheel 75 moves along the inner curved surface 62' of the cam 62. Integral with the arm 77 is an arm 81 formed with a lug 81' which is adapted to engage the roller 66 of the electro-mechanical latch after being set or extended by means of the roller 75 and cams 62 and 63. Normally, the cam 62 passes idly by the roller 75 without engaging the same, as shown in Fig. 11 at 75' in the dotted position, but when the latch 65 is attracted and the stop 49 released by the circuit being closed through the magnet 55, if a sheet of paper is inaccurately placed, the roller 75 will then be forced to the bottom of the groove 61 by means of the spring 54, and as the wheel 56 rotates, the inner curved surface 62' of the cam 62 will engage the roller 75 and force it against the tension or pressure of the spring 80 to reset the transversely located stop 49, which is then retained in an extended position by means of the latch 65. The lift-rod 29 will then be prevented from falling and a sheet of paper can be inserted below the roller 16 and the ejector wheels 25 prevented from operating. The roller 75 resets the latch and stop 49 after it has engaged the bottom of the

groove 61 and is moved by the cams 62 and 63 to reset the latch as described.

Secured to the side of the main gear-wheel 56 is another cam construction 82, shown in side elevation in Fig. 10. This cam is formed with a cut-out portion 83 and an inclined surface 84 with which a roller 85 on the lever 70 engages. This cam is also formed with a second cut-away portion 86 having a beveled surface 87. When the roller 85 engages the inclined surface 84, the lever 70, which is pivoted at the point 88, is moved transverse to the face of the wheel 56 against the tension of the spring 89. The pin 88 is connected to the arm 91 of the lever 91, which latter pivot is pivoted to the sides 92 and 93 of the frame at 94. The lever 91 extends forward as shown in Fig. 5 and to the outer end is attached the link 95 that is connected to the usual device which operate the press cylinder trip so that the type will not engage the same when there is no sheet on the press cylinder. The arm 69, when rocked by the roller 75 in setting the latch and locking the stop-rod 49, simultaneously operates the lever 70 to hold it out of operative position with the cam 82.

The cut-out portion 86 of the cam 82 with its inclined surface 87 is for the purpose of permitting the roller 85 to drop into the cut-away portion 86 without a jar to the mechanism. The purpose of the inclined surface 84 is to force the lever 70 outward away from the operative edge of the cam 82 to render the link 95 inoperative. The next step in the operation of the mechanism is to follow up the movement of the lever 70 by means of the finger 69 which will force (by means of the roller 75) this lever an additional distance outward away from the face of the cam 82, and prevent the roller 85 from engaging the operative edge of the cam 82. When the electro-mechanical lock holds the stop 49 extended, as shown in Fig. 7, the roller 75 is away from the bottom of the groove 61 and during the normal operation of the wheel 56 the roller 75 passes idly over the upper surface of the lower cam 62, but when the latch is tripped or withdrawn by the circuit being closed the roller engages the bottom of the groove 61 and is then forced inward by means of the cam 62 and brought into engagement with the cam surface 63, the outer face of which is higher than the outer surface of the cam 62, to reset the latch and stop 49. The electro-mechanical latch is secured to the frame by means of the bracket-arm 96 by means of the screws 97.

The cam 51' which causes the lift-rod 29 to operate is provided with an adjustable contact device 98 secured in place by means of the slot-bolt connection 99. This contact device engages a fixed contact device 100 to

which the wires 101 and 102 are attached, wire 102 being connected to one terminal of the electro-magnets 55, a wire 103 being connected to the other terminal of the magnets 55 which extends to the sheet-contact devices 104, 105 and 106 which are connected in parallel with the wires 101 and 103. A detail view of the sheet-engaging contact is shown in Fig. 3, wherein the contact-carrying plate is shown at 107, a block of insulation at 108, to which is secured a contact wire 109, a pivoted finger 110 which engages the wire 109 at 111. A spring 112 which is attached to the finger 110 normally closes the contact 111. The source of electrical energy is supposed to be connected at the point 113. The finger 110 is located in a slot or opening 110' in the plate that is secured to the press-feed table and, as shown, extends down below the surface of the table to prevent the paper gaining access below the finger when the sheet is placed on the table 10. The operation of the sheet-engaging mechanism shown in Fig. 3 is as follows: When a sheet of paper is placed on the press table 10 with two of its edges engaging each of the pivoted contact fingers 110 and plates 107, each finger is moved on its pivot against the tension of the spring 112 to open the circuit to the magnet 55 at the contact point 111 (see Fig. 3). If the sheet is accurately positioned for printing on the press-board 10 it is drawn into the press by means of the usual paper gripping fingers 35 (not shown). Simultaneously with the operation of the gripping fingers to draw the sheet into the press the rod 13 is rocked by the usual press mechanism to elevate the contact plates 107 to allow the sheet thereunder by the contact supporting arms which are secured to the rocking shaft 13.

The operation of the mechanism is as follows: When a sheet to be printed is placed on the press feed board 10 against the contact fingers 110 of the contact devices 104, 105, and 106 and the stop-plate 107, if the sheet is accurately positioned so that all of the contacts at 111 are opened, there will be no current through the magnet 55. Should, however, one of the contacts at 111 be left closed, the circuit to the magnet 55 will be closed and the same energized, which will cause the armature 55' of the latch to be attracted, with the result that the stop 49 will be withdrawn, permitting the lift-rod 29 to pass by the stop 49 and allowing the roller 16 to engage the press cylinder 11 and the sheet-ejecting wheels 25 to engage the inaccurately fed sheet of paper and eject the same. When this operation takes place, the roller 75 is permitted to move inward and engage the bottom of the groove 61 to reset the latch mechanism, as described. This roller follows along the inner curved sur-

face 62' of the cam 62 and pushes the arm 65 81 back into the locked position shown in Fig. 7. At the same time the stop 49 is projected outward and the finger 69 follows up the movement of the lever 70 on its pivot 88 to move the roller 85 out of the path 70 of the cam 82. When the machine is tripped to eject a sheet, the roller 85 engages the cam 82 to operate the levers 70 and link 95 to automatically throw the press cylinder away from the type-form to prevent its receiving an impression thereon in the usual manner. If the sheet is accurately fed to the machine, the cam 62 passes idly by the roller 75, as described, and the roll 85 is held out of engagement with the cam 82 and the levers 70, 91 and link 95 remain idle, permitting the sheet to receive its impression. The press cylinder 11 is then operated by means of the usual press cylinder trip devices, which do not form any part of the present invention.

From the description it will be seen that I have produced an inaccurately-fed sheet-detecting device that can, by reason of its compact structure of lever mechanism, be placed or attached to machines now in use, which have the uprights 12 and gear 12'.

The term "type" has reference to a printing form that is either flat or circular in form.

The feed-board at its forward edge is supplied with a flexible or elastic tongue 110' shown in Figs. 1 and 3. The opening 110' in the flexible tongue receives the contact-finger 110, as shown in these figures.

It should be stated that the guide contact devices 105 and 106 against which the sheet of paper is placed to accurately position the same are secured to, and form a part of the usual printing press construction. These contact devices are automatically raised and lowered by the press mechanism at the proper time to allow the sheet of paper to be fed to the press cylinder after it is accurately positioned. In practice the contact guides 105 and 106 are mounted on arms that are attached to an oscillating rod which is parallel with the rod 13, and, as stated these guides are raised and lowered by the usual press mechanism.

What I claim is,

1. In an inaccurately-fed sheet-detecting device for printing presses, the combination with the press impression-cylinder, of stop devices against which the sheet is placed to position the same, an electrical contact on each stop device operated by the sheet, a circuit connecting the contacts, sheet-rejecting devices, an electro-mechanical latch included in the circuit to maintain the rejecting devices inoperative when the sheet is accurately located, a main or master-gear wheel, a contact operated thereby to periodically

open and close the circuit, said wheel having a groove formed therein, an arc-shaped cam in the groove, and means comprising a roller mounted on a slidable rod to engage the cam to effect the reset of the latch after the machine has been tripped to permit the sheet-rejecting devices to operate.

2. In a machine of the class described, comprising, in combination, a main wheel having a groove therein, cams in the groove, a trip-mechanism, a latch-device to retain the trip-mechanism inoperative, a second cam on the main wheel, a device normally retained in an inoperative position by means of the latch-device but when released engages the bottom of the groove to be reset by said cams, the second cam being designed to move the press cylinder away from the printing form when a sheet is inaccurately placed, and connecting mechanism between the second-mentioned cam and the press cylinder.

3. An inaccurately-fed sheet-detecting mechanism for printing presses, comprising, in combination, with the feed-board, of circuit-closing guide devices thereon and against which the edge of the sheet engages, means comprising wheel members to eject the sheet should any one of the guide-devices remain closed during the positioning of the sheet, an electro-mechanical latch-device to maintain the sheet-ejecting means inoperative, connections from the guide-devices to the latch-device, a timing device in the circuit, means comprising a reciprocating rod, a bracket on the rod, a cam-operated lever connected to the reciprocating rod, and a stop device engaged by the lever to limit the downward movement of the sheet-ejecting means, and means to permit the sheet-ejecting means to operate when the circuit to the latch-device is closed.

4. In a machine of the class described, the combination, guide-members to position a sheet of paper, sheet-ejector devices, stop-devices to limit the downward movement of the ejector devices with relation to the press feed-board, a latch to retain the stop-device in an operative position, devices to operate the stop-devices, means to reset the latch, means to move the press cylinder to its non-printing position when the sheet is inaccurately positioned, and means to operate the ejector devices when the sheet is inaccurately placed on the press feed-board.

5. The combination, a main-wheel formed with a groove therein, cams in the groove, a cam attached to the wheel, a press impression cylinder and operative connections between the cam and said cylinder to move the cylinder to an inoperative position when a sheet of paper is inaccurately fed, a latch-device, guide means to position the paper, sheet-ejector means operable from the press

cylinder, means operated by the cams in the groove to operate the latch-device, and means controlled by the latch to permit the sheet-ejector means to operate.

6. In an inaccurately-fed sheet-detecting and rejecting mechanism for printing presses, the combination, with the press feed-board, of a fixed rod, a frame pivotally attached thereto, a drive roller adapted to engage the press cylinder but normally out of engagement therewith, means to permit the roller to engage said cylinder, a shaft, sheet-ejector rollers thereon, connections between the drive roller and the last-mentioned rollers to operate the ejector rollers, means independent of the drive roller to vary the pressure of the ejector rollers on the press feed-board, and means to render the ejector rollers operative to remove a sheet when inaccurately positioned with relation to the press cylinder.

7. In a machine of the class described, the combination with the press feed-board, of sheet-positioning guides against which the edges of the sheet engage to position the same, rotary ejector means normally out of engagement with said board to permit the sheet to be inserted and positioned, a lift-rod, a sliding stop to normally support the ejector means, means adapted to be controlled by the sheet to release the lift-rod and permit the ejector-means to operate, and means to reset the lift-rod to render the ejector-means inoperative.

8. In an inaccurately-fed sheet-detecting mechanism, the combination with the press impression-cylinder, of guide-devices to position the sheet, a roller normally out of contact with said impression-cylinder, sheet-ejecting rollers designed to engage the sheet to reject the same if inaccurately located with relation to the guide-devices and operable from the first-mentioned roller, connecting means to reverse the direction of rotation of the ejecting rollers with relation to the impression-engaging-roller, means to cause the rollers to operate upon the placing of a sheet in an inaccurate position, and means to move the rollers to an inoperative position, as described.

9. An ejector mechanism for printing presses, comprising a cam, a lever operable therefrom, a lift-rod operable from the lever, an angular-shaped bracket secured to the upper end of the lift-rod, a sheet ejector device, an arm to support the sheet-ejector device and operable from the bracket, a stop-device, said sheet-ejector device being normally sustained in an inoperative position by the stop-device with relation to the feed-table, means to withdraw the stop-device to permit the ejector rollers to operate, and means to reset the stop-device to render the ejector device inoperative, as described.

10. A reset mechanism for printing presses, comprising, in combination, means to eject a sheet of paper, a main-wheel having a groove therein, two cams in the groove, 5 a latch-device, means operable by the cams to reset the latch after the operation of the sheet ejecting means, the cams being normally inactive after the latch-device has been reset, one of the cams being of greater

height than the other to effect the final re-setting of the latch and whereby the latch-reset means is normally inoperative if the sheet is accurately placed, as described. 10
